[57] CLAIM

The ornamental design for a right angle drilling apparatus for drilling wiring holes and the like through building studs, joists, rafters and the like, as shown and described.

DESCRIPTION

FIG. 1 is a side elevation view of a right angle drilling apparatus for drilling wiring holes and the like through building studs, joists, rafters and the like, embodying our new design, the opposite side being substantially the mirror image thereof;

FIG. 2 is a top plan view thereof, viewed from above FIG. 1;

FIG. 3 is an end elevation thereof, viewed from the left of FIG. 1;

FIG. 4 is an end elevation thereof, viewed from the right of FIG. 1;

FIG. 5 is a bottom view thereof, viewed from below FIG. 1.
